MOUNTING BRACKET FOR SUPPORTING A
DIGITAL TRANSMITTER OR THE LIKE IN
VEHICLES

Robert S. Reynolds, Cupertino, Calif., assignor to
E-Systems Incorporated, Dallas, Tex.

Filed Nov. 26, 1971, Ser. No. 202,736

Term of patent 14 years

Int. Cl. D8—08
U.S. Cl. D8—233

FIG. 1

FIG. 1 is a perspective view of a mounting bracket for supporting a digital transmitter or the like in vehicles showing my new design;

FIG. 2 is a side elevational view thereof;

FIG. 3 is a front elevational view thereof as viewed on line 3—3 of FIG. 2;

FIG. 4 is a top plan view thereof as viewed on line 4—4 of FIG. 2; and

FIG. 5 is a rear elevational view thereof as viewed on line 5—5 of FIG. 2.

I claim:

The ornamental design for a mounting bracket for supporting a digital transmitter or the like in vehicles, as shown.
